CLAIM

The ornamental design for a display screen or portion thereof with graphical user interface for display of content upload, as shown and described.

DESCRIPTION

The sole FIGURE is a front view of a display screen or portion thereof with graphical user interface for display of content upload showing our new design.

The dotted horizontal rules are not claimed. The broken line showing of the display screen or portion thereof and the remainder of the graphical user interface forms no part of the claimed design.

1 Claim, 1 Drawing Sheet
